US00D866467S

(12) **United States Design Patent** (10) **Patent No.:** **US D866,467 S**
(45) **Date of Patent:** **** Nov. 12, 2019**

(54) **ELECTRIC POWER CONTROLLER**

(71) Applicant: **ELLENBERGER & POENSGEN GMBH**, Altdorf (DE)

(72) Inventor: **Judith Tenzer**, Ulm (DE)

(73) Assignee: **Ellenberger & Poensgen GmbH**, Altdorf (DE)

(**) Term: **15 Years**

(21) Appl. No.: **35/502,772**

(22) Filed: **Mar. 9, 2017**

(80) **Hague Agreement Data**

Int. Filing Date: **Mar. 9, 2017**

Int. Reg. No.: **DM/095422**

Int. Reg. Date: **Mar. 9, 2017**

Int. Reg. Pub. Date: **Apr. 7, 2017**

(51) **LOC (12) Cl.** **13-03**

(52) **U.S. Cl.**

USPC **D13/123**

(58) **Field of Classification Search**

USPC D13/123, 160, 159, 158, 162, 147, 133, D13/110; D15/5; D14/313; 335/14; 218/40; 439/884; 174/541

CPC G01K 7/023; H01H 71/70; H01H 9/34; H01H 9/0066

(57) **CLAIM**

The ornamental design for an electric power controller, as shown and described.

DESCRIPTION

1.-2. Equipment for control of electric power

1.1 : Perspective

1.2 : Left

1.3 : Right

1.4 : Top

1.5 : Bottom

1.6 : Front

1.7 : Back

1.8 : Perspective

In the reproductions, the broken lines are for the purpose of illustrating environment only and form no part of the claimed design.
